UNITED STATES PATENT OFFICE.

JOHN A. ELSESOR, OF PORTLAND, OREGON, ASSIGNOR TO ELERT A. HILL, OF ASTORIA, OREGON.

COMBINATION-LOCK.

1,147,794.

Specification of Letters Patent.

Patented July 27, 1915.

Application filed September 17, 1914. Serial No. 862,247.

To all whom it may concern:

Be it known that I, JOHN A. ELSESOR, a citizen of the United States, and a resident of the city of Portland, county of Multnomah, State of Oregon, have invented a certain new and useful Improvement in Combination-Locks, of which the following is a specification.

The object of my invention is to provide 10 a combination lock operated by depressible finger keys, which have to be selectively operated by the person possessing the right combination in order to unlock the lock.

My invention may be used on bolt locks 15 and other locking devices, but it is especially devised for locking the switch element of electric ignition circuit of internal combustion engines, as in automobiles, motor boats, etc. In this connection my device provides 20 a keyless lock rendering the machine incapable of use except to the person possessed of the right combination of my lock.

In illustrating and describing my invention I have shown the same as applied 25 under the last named condition. In such use of my invention, I attain my object by supporting the movable member of the switch, in the electric circuit, on a pivoted bail, and combining with the latter a latch element 30 normally locking such bail against motion; the latch element being operated by a finger-key for releasing the same from the bail; and in order to complicate the locking mechanism and render the same difficult to operate 35 by a person not possessed of the right combination, I provide further interfering latch-elements, normally disengaged from the pivoted bail and adapted to be thrown into locking engagement therewith by operating 40 the finger-key with which such interfering latch element is provided; also, I provide spring-controlled keys adapted to simulate the resistance and touch of the keys of the latch-elements so that the operator of 45 the lock, not having the right combination, would be deceived, by operating the blind spring keys, into the belief that he was manipulating the keys that were connected with the latching elements of the combination 50 lock.

Other features of my invention are hereafter fully described, reference being had to the accompanying drawings, in which:

Figure 1 is a front elevation showing my device as applied for controlling the electric 55 ignition circuit of an internal combustion engine; Fig. 2 is a right-end elevation of the device shown in Fig. 1, with a portion of the casing broken away so as to illustrate the electrical switch connections; the full 60 lines show the switch open, and the broken lines show the same closed; Fig. 3 is a left-end elevation of the parts shown in Fig. 1, with a portion of the casing broken away so as to illustrate the spring which normally 65 holds the device in its unlocked state; Fig. 4 is a sectional view taken approximately on the line 4-4 of Fig. 1; Figs. 5, 6 and 7 are larger-scale sectional views taken approximately on the line 5-5, 6-6, and 7-7 respectively; and Fig. 8 shows an alternate construction, which may be used in place of the construction shown in Fig. 5.

For convenience I shall term the electric switch element of the electric ignition circuit as the controlling mechanism. The case, *a*, contains my lock mechanism. The case is provided at its right end (with respect to Fig. 1 and as shown in Fig. 2) with a separate compartment in which the electrical switch elements are contained, consisting of the stationary member *b* and the movable member *c*; the latter being carried on the bail *d*, pivoted between the ends of the case, *a*, on an axle *e*. The pivoted bail is controlled by a spring *f*, which normally holds the bail as shown in broken outline in Fig. 3, and when so arranged the electric switch will be closed, as apparent from Fig. 2. On the projecting outer end of 80 the axle, *e*, is affixed a crank *g*, for rotating the bail against the tension of the spring *f* and into its inactive position. When in this position it is locked against movement by a latch element of the character illustrated 85 in Fig. 4. It consists of a latch-bar *h*, pivoted at *h'*, and normally held in locking engagement with the cross piece of the bail, *d*, by a spring *h*², as shown in Fig. 4. The latch-bar *h* is provided with a spring-arm 100 *h*³, against which bears the stem of a depressible key *h*⁴, controlled by a spring *h*⁵. By pressing in the key *h*⁴, its stem will push against the spring arm *h*³ of the latch-bar *h* and move the latter out of engagement 105 with the bail *d*, as evident from Fig. 4, and

as soon as the bail, d , is released the spring f will operate to pull the same into its active position.

- In order to make my lock more difficult to manipulate by a person not possessed of its combination, I prefer to provide a plurality of latch elements, each operating to normally hold the bail, d , against movement when placed in its inactive position.
- These secondary latching means are illustrated in Fig. 5. They consist of a latch-bar i , pivoted at i' and controlled by a spring i^2 . In the lower end of the latch-bar i is provided a spring arm i^3 . On the pivot or axis, i , is pivoted a supplemental latch-bar j , provided with a stud j' adapted for engaging with a recess i^4 of the latch-bar i . The supplemental latch-bar j is controlled by a spring j^2 . To the supplemental latch-bar j is connected the stem of the spring-controlled key j^4 . The last described latch element is operated as follows: First the key j^4 must be pressed in, which operates to throw the supplemental latch-bar j against the latch-bar i , releasing the latter from, and engaging the former with, the bail d . The key k must then be pushed in, in so doing bringing its stem k' in front of the spring arm i^3 , and thus preventing the latch-bar i from returning to its normal position. The key j^4 must then be released, and thereupon the secondary or last described latch element is entirely released from the bail d ; and if the latch element comprising the latch bar h (shown in Fig. 4) has previously been operated so as to release the bail d , the spring f of the latter will act to throw the same into its active position.
- In order to further complicate my lock, with respect to the manipulation required of its keys in order to release the bail d , I provide another latch element comprising a latch-bar l , operated by a key l' , and in all respects being a duplicate, with respect to function and mode of operation, of the latch element including the latch-bar h shown in Fig. 4. Therefore a lock comprising the latch-bars h , i , j , l , will require the co-operative manipulation of the keys h^4 , j^4 , k , l' .
- To still further complicate and baffle the unauthorized manipulation of my lock, I provide interfering latch elements represented by m , n , operated by keys m' , n' , and a further interfering latch element o , operated by a key o' , an interfering latch element comprising latch-bars p , operated by a key p' , and a latch bar q , operated by a key q' . The interfering latch elements including the latch-bars m , n , o , p , q are thus normally out of engagement with the bail d , and are thrown into locking movement with the latter by depressing in their keys.
- A plurality of interfering latch elements

similar in construction to the elements shown in Fig. 6 is provided in my lock, the same being disposed as shown by Fig. 1, in which all these elements are distinguished by having the same reference characters to designate their keys.

To further complicate my lock and baffle its unauthorized manipulation, I provide a plurality of blind keys as r , controlled by springs r' . The respective springs of all the keys of my lock are adapted to give each key the same touch, and thus the touch and resistance of the blind keys r will simulate the touch and resistance of the keys which are connected to and operate the described latch elements of my device.

To permit the bail d to be drawn down by its spring f , when released, and also permit the same to be brought back into locking engagement with the latch elements by the operation of the crank g , I construct the latch bars as shown, each having a portion as s adapted for being brought into engagement with the cross piece d' of the bail d , and having beveled surfaces as t , on which rides the cross piece d' of the bail d , and causes said cross piece to move the latch-bar out of the way when the crank g is rotated to restore the bail d to its inactive position.

In Fig. 8 I have shown a latch element comprising two co-operating members which are required to be co-operatively manipulated through the medium of their connected keys, in order to release the bail d . This latch mechanism consists of a latch bar u , adapted for normally being in engagement with the cross piece d' of the bail d , as shown in Fig. 8. A latch-bar v is provided with a stud v' and the latter is engaged by a hook arm u' , carried by the latch-bar u . The latch-bar u is operated by a connected finger u^2 . In order to release the bail d from the latch element shown in Fig. 8, the latch key u must first be pressed in, the stem thereof disengaging the spring hook arm u' from the stud v' of the latch-bar v , and the key u^2 may then be pressed in, with the effect of disengaging the latch bar u from the bail d .

The two-membered latching device shown in Fig. 8 may be substituted in place of the two-membered latching device consisting of elements i , j and keys j^4 , k shown in Fig. 5.

The latch-bar x in Fig. 8 is an interfering latch element similar to the interfering latch element n in Fig. 5.

y represents stud pins or stops for the bars to bear against.

The operation of my device is self evident from the foregoing description of its construction.

As self evident, the positions of the respective latch-bars and the blind keys may be changed to effect a great number of varying combinations.

I claim:

1. In a lock a locking element consisting of two spring-controlled pivoted latch-bars, one of such latch-bars being in active or 5 engaging position, an operative connection between said two latch-bars adapted to cause the inactive one thereof to be thrown into its active position when the other is thrown into inactive position, an operating key connected with one of said latch-bars, and key-operated means for temporarily interrupting said operating connections between said latch-bars.

2. In a lock a locking element consisting 15 of two spring-controlled pivoted latch-bars, one of such latch-bars being in active or engaging position, an operative connection between said two latch-bars adapted to cause the inactive one thereof to be thrown into 20 its active position when the other is thrown into inactive position, an operating key connected with one of said latch-bars, key-operated means for temporarily interrupting 25 said operating connections between said latch-bars; another spring-controlled latch-

bar normally in its engaging position, and an operating key connected with such latch-bar.

3. In a lock a locking element consisting of two spring-controlled pivoted latch-bars, 30 one of such latch-bars being in active or engaging position, an operative connection between said two latch-bars adapted to cause the inactive one thereof to be thrown into its active position when the other is thrown 35 into inactive position, an operating key connected with one of said latch-bars, key-operated means for temporarily interrupting said operating connections between said latch-bars; another spring-controlled latch- 40 bar normally in its engaging position, and an operating key connected with such latch-bar; another spring-controlled latch-bar normally out of its engaging position, and an operating key connected with such latch- 45 bar.
